COMBINATION BED LAMP AND RADIO

Marcy D'Onofrio, Richmond Hill, N. Y.

Application June 18, 1935, Serial No. 27,150

2 Claims. (Cl. 312—7)

This invention relates to a combination bed lamp and radio.

One of the objects of the invention resides in a combined bed lamp and radio for attachment to the head of a bed to provide illumination and radio entertainment to a person lying in bed, and which will be found useful to persons confined to bed by illness or during convalescence, as well as for home use in general while resting or reading in bed.

Another feature of the invention is the provision of a combination bed lamp and radio in which the radio control panel is positioned face downward to present the control knobs for view and within the reach of a person lying in bed, the panel board having means for reflecting the light downward therefrom for reading purposes.

A further feature of the invention is the provision of a combined bed lamp and radio which is compact and in which the radio parts are shielded from view when the illuminating lamps are lighted, even though the parts are enclosed in a translucent shade covering.

A still further object of the invention is the provision of a combination bed lamp and radio which is light in weight and portable to enable its removal from the head of a bed when cleaning the head of the bed, or to permit the article to be carried from place to place for radio entertainment purposes should it be so desired.

With these and other objects in view, the invention resides in the certain novel construction, combination and arrangement of parts, the essential features of which are hereinafter fully described, are pointed out in the appended claims, and are illustrated in the accompanying drawing, in which:

Fig. 1 is a perspective view of my combination bed lamp and radio.

Fig. 2 is a vertical longitudinal sectional view on the line 2—2 of Fig. 1.

Fig. 3 is a vertical transverse sectional view on the line 3—3 of Fig. 1.

Fig. 4 is a perspective view of a modified form of the invention.

Referring to the drawing by reference characters, and more particularly to the form of the invention shown in Figs. 1 to 3, inclusive, the numeral 10 designates my improved combination bed lamp and radio in its entirety. The combination article 10 includes a wire frame structure 11 of substantially rectangular configuration although the frame may be of various shapes or designs to suit the taste of the user. Fixedly secured to the frame 11 and closing the rear open

side thereof, is a rigid back wall 12 while fixedly secured to the back wall 12 and closing the open bottom of the frame structure, is a panel board 13 which may be made of metal or other composition of material if so desired. The panel board 13 is also secured to the lower rails of the frame structure 11 and is formed with an inwardly bent portion to provide a lamp receiving recess and light reflector 14. An electric lamp 15 disposed within the recess reflector and inserted into a socket 16 fixedly mounted to the panel board as shown in Fig. 2 of the drawing.

Contained within the frame structure 11 adjacent the rigid back wall 12 is a radio receiving set 17 which includes the usual electron tubes, tuning instrument, and amplifier, the chassis of the set being supported upon the horizontally disposed panel or board 18 which is fixedly secured to the rigid back wall 12 and which extends forwardly as shown in Fig. 3 of the drawing. The radio set 17 includes two control knobs 19 and 20, which are disposed upon the under side of the instrument panel 13. The knob 19 constitutes a switch and volume control as is customary in midget radio sets, whereas the knob 20 controls the operation of the tuning instrument. The knob 19 is provided with the usual indicating pointer which traverses a dial 22 while the knob 20 is provided with an indicating pointer 23 which traverses a dial 24. The dials 22 and 24 are so arranged that they may be read by a person in a lying posture beneath the article and the control knobs are conveniently located for manipulation by a person in such posture.

The radio set 17 also includes a loud speaker 25 which opens through the top of the frame structure and which is supported by a bracket 26 fixedly secured to a reflector 27 which extends from the baseboard 18 upwardly to engagement with the rigid back wall 12 adjacent the top 40 thereof. The upper portion of the reflector 27 is curved and is provided with end walls for enclosing the radio set 17 from view, the back wall 12 and the panel board 13 co-acting with the reflector in this respect.

Fixedly secured to the reflector 27 is a bracket 28 which carries a socket 29 in which an electric illuminating lamp 30 is mounted.

The open side of the frame structure 11 together with the combined instrument board and reflector 13 are covered with a translucent shade material 31, which may be silk, parchment or the like. The material 31 is drawn taut over the frame structure and spans the recess reflector 14, but permits light from the lamp 15 to pass down- 55

wardly. The lamp 30 illuminates the body of the article when lighted, and the article as a whole has the appearance of an ordinary bed lamp.

The wire rail forming the frame structure 11 may be covered with tape 32 wound spirally there-around, and to which the shade material 31 is stitched. The rigid back wall 12 is provided with an opening 33 for the passage of an electric conductor 34 having a plug 35 at its free end for insertion into the socket of an electric outlet. Also entering the lamp through the opening 33 is a lead-in antenna wire 35' for the radio set.

For the purpose of supporting the article upon the head of a bed with the instrument panel fac-ing downwardly, I provide a pair of hook members 36 which are screwed to the back wall as at 37. The hook portions of the members 36 are enclosed by tubular rubber cushion members 38 to prevent scarring of the head of a bed when the article is hung thereon and suspended by the hook mem bers.

For the purpose of controlling the turning on and off of the electric current to the lamps 15 and 30, I provide snap switch 39 on the instrument panel 13, so as to be within easy reach of the person when lying beneath the article.

From the foregoing description it will be seen that I have provided a combined bed lamp and radio, the lamp supplying the necessary illumina-tion to enable the person to read while lying in bed with the article supported upon the head of a bed. The radio control knobs and light switch are so positioned as to be within easy reach of a person lying in bed.

In Fig. 4 of the drawing, there is shown a slightly modified form wherein the cabinet or casing is constructed wholly of wood or other rigid mate-rial 40, the instrument panel 41 being mounted in the bottom of the casing and having a light opening 42 therein for the passage of light from a lamp contained within the casing which is equiv-alent to the lamp 15 shown in the previous form. Instead of positioning the loud speaker in the top of the casing as shown in the previous form, the front wall 43 of the casing 40 is provided with

a grill 44 and the mouth of the speaker is dis-posed against the grill to enable the sound to be emitted from the front of the casing. In this form, however, the entire article is not illum-i-nated as is possible in the previous form, but 5 sufficient light may pass through the opening 42 to supply the user with illumination for reading purposes. It will, of course, be understood that the back wall of the casing 40 is provided with hooks similar to those shown at 36 in the pre-10 vious form.

While I have shown and described what I con-sider to be the most practical embodiments of my invention, I wish it to be understood that such changes as come within the scope of the appended 15 claims may be resorted to if desired.

Having thus described the invention, what is claimed, is:

1. A combined radio cabinet and lamp shade adapted to be supported in an elevated position 20 relative to the user thereof and comprising a rigid back wall, a rigid skeleton frame carried by said rigid back wall and extending forwardly thereof, a rigid bottom wall connected to said frame and back wall, and having a recess in its under surface for mounting a lamp therein, a translucent shade covering drawn taut about said frame and bottom wall and secured thereto and a radio control panel positioned at the under side 25 of the bottom wall and outwardly of the shade covering.

2. A radio cabinet adapted to be supported for overhead use and comprising a casing, having a bottom and rear walls, the under side of the bot-tom of the casing constituting the instrument 35 control panel of a radio receiver, and said bot-tom wall also having a recess therein adjacent the control panel and forming a light reflector, a lamp mounted in the recess and a translucent cover extending over the recess for permitting 40 light rays produced by said lamp to pass down-wardly therefrom for reading purposes and for illuminating the exterior of said bottom wall.
